UNITED STATES PATENT OFFICE.

FRANK FREDERICK WILLIAM DOERING, OF HIBBING, MINNESOTA.

VAPOR AND AIR INTENSIFIER AND CARBURETOR ATTACHMENT.

Application filed July 10, 1922. Serial No. 573,827.

To all whom it may concern:

Be it known that I, FRANK FREDERICK WILLIAM DOERING, a subject of the King of Great Britain, and residing at Hibbing, in 5 the State of Minnesota, one of the United States of America, have invented certain new and useful Improvements in Vapor and Air Intensifiers and Carburetor Attachments, of which the following is a specification.

This invention relates to improvements in vapor and air intensifiers and carburetor attachments designed for use on automobiles and like vehicles, and the objects of the invention are to facilitate drawing a mixture of air and water vapor from a radiator and delivering the said mixture to the carburetor in the proper proportions to form with the combustible fluid a good explosive mixture; 10 to deliver air to the radiator adjacent to the normal water level thereof, so that it will be beneath the water vapor, and thus cause a greater amount of water vapor to be delivered to the carburetor, and to so control 15 the valve mechanism to permit of the carburetor functioning in the manner best calculated to increase its efficiency.

Further objects are to connect the carburetor with the radiator by means of flexible conduit, so that, in the event of jarring taking place, there is no possibility of the conduit becoming broken, and undue vibration will not be transmitted to the carburetor and interfere with the well working thereof, and generally to adapt the several parts to better perform the functions required of them.

With the above and other objects in view, the invention consists essentially of the improved construction particularly described and set forth in the following specification and in the accompanying drawings.

In the drawings:

Figure 1 is a side elevation of an automobile radiator showing the overflow pipe arranged to control the height of water line, and a conduit connecting the radiator and the carburetor through a three-way valve or cock, and water trap to prevent the water 40 entering the carburetor.

Figure 2 is a vertical section of the radiator showing the position of the overflow pipe, air inlet pipes and vapor feed pipes.

Figure 3 is a fragmentary vertical section of the inlet of the radiator showing the 55 funnel designed to close the vapor feed pipe, when pouring water into the radiator.

Figure 4 is a vertical fragmentary section of the radiator showing a vapor chamber attached thereto with a suitable connection for the flexible conduit which is connected to the radiator.

Figure 5 is a side elevation partly in section of the air inlet valve.

Figure 6 is a vertical section of the float 65 chamber.

Referring to the drawings, in which like characters of reference indicate corresponding parts in all the figures, and in which:

A designates a radiator provided with an 70 overflow pipe 10, the upper end of which extends into the radiator, while the lower end projects below the radiator. This pipe when not draining water from the radiator will help to deliver air thereto. B designates a carburetor of any well-known description. In accordance with my invention I provide a plurality of vertically disposed air inlet pipes 11 which extend through the top wall of the radiator A and terminate 75 just at the normal water line of the radiator. In the space between the normal water level and the upper wall of the radiator, a mixture of water vapor and air will be formed, and this mixture is delivered to a vapor pipe 85 12, the inlet end of which is in the form of a gooseneck and extends through the rear wall of the radiator and upwardly into the highest point thereof.

The vapor pipe 12 is connected by a flexible conduit 13 to a three-way valve 14, which is attached to the air inlet 15 of the carburetor B or the fuel intake as found convenient. The valve 14 is controlled by a lever 16 actuated by a rod 17 which extends 90 through the dash board to a point adjacent to the driver's seat. A water trap 9 is provided adjacent to the valve 14 and is formed with an angularly disposed and upwardly extending baffle wall or shield 8 which pro- 100

jects towards the flexible conduit 13, and below this baffle wall, a water chamber 7 is provided formed with a discharge outlet 6.

5 When an automobile or engine equipped with this device is in use, the air which passes through the overflow pipe 10 or the air inlet pipe 11 is delivered into the radiator at a point adjacent to the normal water lever 10 therein and below the water vapor, so that a good mixture of air and water vapor is obtained and delivered to the vapor pipe 12.

This mixture of water vapor and air is drawn through a flexible conduit 13, the 15 three-way valve 14 and into the carburetor B or manifold C, and is intermixed with the motive fluid, so that the explosive mixture delivered to the cylinder will consist of properly atomized combustible fluid, 20 water vapor and air, in the proportions best calculated to give proper results. No water in the liquid state can pass the baffle wall 8, so that the only water delivered to the carburetor from the radiator will be in 25 the form of water vapor suspended in the air which is drawn through the radiator to the carburetor.

If it is desired to supply the engine with ordinary atmospheric air not mixed with 30 water vapor, then on actuation of the three-way valve 14, air may be drawn into the carburetor at 15 through an opening 18 in the valve 14.

It should be particularly noted that, when 35 replenishing the radiator A with water, it is advisable that no water could enter the vapor pipe 12 and, to this end, I provide a funnel 19 closed at the lower end and provided with a downwardly projecting flange 40 5 which embraces the bore of the said vapor pipe, and this funnel has perforations 4 in its side walls just above the bottom wall, and through these perforations, the water poured into the funnel issues and is delivered to the 45 radiator. In this way, the radiator A may be filled with water without any of the water entering the vapor pipe and without any serious drawbacks resulting from the filling 50 operation which would otherwise occur if water entered the said vapor pipe.

Again, in some cases, the inlet of the radiator may be too small to accommodate the vapor pipe 12 therein, and, under such circumstances, I provide a vapor chamber or dome 21 having a threaded nipple 22 which screws on the inlet neck 22^a of the radiator. An inlet 23 is provided which will be normally closed by a cap, and towards the lower side of the vapor chamber or dome a nipple 60 24 extends which is adapted to be connected to the flexible conduit 13. Inner partitions 25 are provided which form passageways 26 with which the nipple 24 communicates, and, in filling water into the radiator, 65 there is no possibility of the said water pass-

ing through the conduit 24 into the flexible conduit 13.

When using the vapor chamber or dome, an adequate supply of water vapor and air will be obtained, and there is no possibility 70 of water splashing or otherwise entering the nipple 24 so that the mixture of water vapor and air delivered to the conduit 13 will be in proper condition to be mixed with the combustible fluid passing through the carburetor B.

In Figure 5 I have illustrated an air inlet valve which is connected between the three-way valve 14 and the water trap 9, as shown in Figure 7. The object of this 80 valve is to permit air to enter into the conduit 13 when the motor is running at high speed, and to form a more accurate mixture of moisture in proportion to the speed, and to prevent heavy suction through the 85 conduit 13 and pipe 11 which otherwise would cause water to enter the motor. This valve comprises a valve cage 27, valve 28, spring 29, flat washer 30, and a nut 31 for adjusting the tension on the valve to regulate 90 the amount of air to be let in.

D is the float chamber comprising a short vertical cylinder secured to the radiator A by a bracket 32 having slots in which are secured bolts with nuts 33 whereby the 95 chamber can be adjusted vertically. 34 is a float in chamber D, and 35 is a tube extending from the bottom of the chamber D to the top level of the float and having therein a needle valve 36. This valve is suitably secured on the float and through the holder 38. A water pipe 39 connects the lower end of the float chamber to the radiator while an air pipe 40 connects the upper end of the chamber to the radiator.

is so set as to open or partly open the passage to the top of the pipe 12, then a partial vacuum will result in the open upper part of the radiator. The air then rushing down 5 through the tubes 11 will strike the surface of the water, forming a heavy vapor which will be carried to the carburetor.

It is found that the water in the radiator vaporizes so fast that it needs constant 10 replenishing to keep its surface immediately under the ends of the tubes 11, and therefore the float chamber D and auxiliary tank 14^a are provided. Of course when the water surface in the radiator is high enough then 15 the float 34 floats. When the float lowers, then water will flow from the tank through the pipe 16^a to the chamber and, because of the connections 39, the surface in both the chamber and the radiator will be equalized, 20 and raised. The necessary pressure needed in the tank for feeding the water through the pipe 16^a is created by the exhaust of the engine which passes up through the pipe 42. The check valve 43 prevents the 25 escape of the pressure back through the pipe and enables a considerable pressure to be stored in the tank after the engine has stopped or is running at a very slow speed.

As the vaporization and replenishing of 30 the water in the radiator is very rapid, it does not become hot enough to cause steam. The moisture drawn to the engine is vapor, and this is found preferable to steam as the latter, when mixing with gas to be exploded, 35 has already expanded to a considerable extent, while the vapor aids in the combustion by expanding when the gas is ignited and not before.

As many changes could be made in the 40 above construction and many apparently different embodiments of my invention within the scope of the claims, constructed without departing from the spirit or scope thereof, it is intended that all matter contained 45 in the accompanying specification and drawings shall be interpreted as illustrative and not in a limiting sense.

The mixture of water vapor and air is controlled by a three-way valve, which is 50 so arranged that the outlet to the carburetor has at all times a full opening. The inlets of the three-way valve from conduit 13 and air inlet 18 are so arranged that, when 13 is half open, the air inlet 18 will 55 also be half open or, if one opening is one-fourth open, the other opening will be three-fourths open; one will work in proportion to the other at any regulation.

What I claim as my invention is:

60 1. The combination with a radiator having an overflow pipe, and the carburetor of an engine, of a three-way valve located between the carburetor and the radiator and connected thereto by conduits, air intake means in said conduits, means for actuating

the valve, and air pipes extending through the top of the radiator and terminating at the lower end adjacent to the normal water level in the radiator.

2. The combination claimed in claim 1 70 in which a vapor chamber is provided in the radiator, and means for connecting the vapor chamber to a conduit connected to the three-way valve.

3. The combination with a radiator and 75 carburetor of an engine, of means for delivering air to the radiator at a point adjacent to the normal water level thereof and drawing the air over the surface of the water, a conduit communicating with the 80 highest point of the radiator to receive a mixture of air and water vapor, a three-way valve connected to the said conduit, and means for connecting the valve to the carburetor. 85

4. The combination claimed in claim 1, in 90 which a water trap is located adjacent to three-way valve and provided with a baffle wall to intercept any water passing through.

5. The combination claimed in claim 1 in 95 which an air intake valve is provided between the three-way valve and the water trap.

6. In combination with the radiator and 100 carburetor of an engine, of means for delivering air to the surface of the water in the radiator, tubular connection between the top part of the radiator and the carburetor, and an auxiliary tank adapted to feed water into the radiator. 105

7. In combination with the radiator and 110 carburetor of an engine, of means for delivering air to the surface of the water in the radiator, tubular connection between the top part of the radiator and the carburetor, an auxiliary tank adapted to feed water into the radiator, and means for retaining the surface of the water in the radiator at a predetermined level.

8. In combination with the radiator and 115 carburetor of an engine, of means for delivering air to the surface of the water in the radiator, tubular connection between the top part of the radiator and the carburetor, an auxiliary tank adapted to feed water into the radiator, and a tubular connection between the tank and the exhaust manifold of the engine. 120

9. In combination with the radiator and 125 carburetor of an engine, of means for delivering air to the surface of the water in the radiator, tubular connection between the top part of the radiator and the carburetor, an auxiliary tank adapted to feed water into the radiator, and a tubular connection between the tank and the exhaust manifold of the engine, said second mentioned tubular connection having a check valve therein.

10. In combination with the radiator and 130

- carburetor of an engine, of means for delivering air to the surface of the water in the radiator, tubular connection between the top part of the radiator and the carburetor, an auxiliary tank and a delivering pipe connecting it to the radiator, said pipe opening near the bottom of the tank, a pressure pipe connecting the top of the tank to the exhaust manifold of the engine, and a check valve in said pressure pipe,
11. In combination with the radiator and carburetor of an engine, of means for delivering air to the surface of the water in the radiator, tubular connection between the top part of the radiator and the carburetor, a float chamber adjacent the radiator and communicating therewith, an auxiliary tank, a pipe connecting the tank to the float chamber, and means for causing water to flow from the tank into the float chamber when the float therein is in lowered position.
12. In combination with the radiator and carburetor of an engine, of means for delivering air to the surface of the water in the radiator, tubular connection between the top part of the radiator and the carburetor, a float chamber adjacent the radiator and communicating therewith, means for adjustably securing the float chamber to the radiator, an auxiliary tank, a pipe connecting the tank to the float chamber, and means for causing water to flow from the tank into the float chamber when the float therein is in lowered position.

In witness whereof I have hereunto set my hand in the presence of two witnesses,

FRANK FREDERICK WILLIAM DOERING.
